UNITED STATES PATENT OFFICE.

ERWIN R. STOEKLE, OF MILWAUKEE, WISCONSIN, ASSIGNOR TO THE CUTLER-HAMMER MFG. CO., OF MILWAUKEE, WISCONSIN, A CORPORATION OF WISCONSIN.

ELECTRIC REGULATOR.

1,361,197.

Specification of Letters Patent. Patented Dec. 7, 1920.

Application filed October 5, 1917. Serial No. 194,850.

To all whom it may concern:

Be it known that I, ERWIN R. STOEKLE, a citizen of the United States, residing at Milwaukee, in the county of Milwaukee and

5 State of Wisconsin, have invented new and useful Improvements in Electric Regulators, of which the following is a full, clear, concise, and exact description, reference being had to the accompanying drawing, forming 10 a part of this specification.

This invention relates to regulators particularly applicable to a proposed electrical apparatus for measuring the flow of fluids but also susceptible of advantageous employ- 15 ment in other relations.

Such proposed fluid measuring apparatus comprises electrical means to supply heat to the flowing fluid and to measure the electrical energy required to maintain a constant 20 temperature difference of the flowing fluid between given points, means including selenium cells to measure the temperature variations resulting from variations in the flow of fluid and an electromagnetic regu- 25 lator sensitive to control by said selenium cells to automatically vary the energy input of said heating means. And the present invention has among its objects to provide a simplified electromagnetic regulator for this 30 and other purposes which will be efficient and reliable in operation.

A further object is to provide for the aforesaid and other purposes a simplified regulator of the "follow up" type and one 35 which will provide for continuous resistance variations as distinguished from step by step variations.

Other objects and advantages of the invention will hereinafter appear.

40 One embodiment of the invention is schematically illustrated in the accompanying drawing as incorporated in a measuring apparatus of the character above specified and the same will now be described.

45 Referring to the regulator, the same comprises a mercury well 1 provided at its lower end with a circuit terminal 2, a reciprocable carbon or other suitable electrode 3 suspended in the mercury, differential elec- 50 tromagnets 4 and 5 having a common plunger 6 supporting said electrode, latching pawls 7 and 8 coöperating with a ratchet extension 9 of said plunger and electromagnets 10 and 11 controlling said pawls. Fur- 55 ther, the regulator comprises a piston 13 at-

tached to the electrode 3 and an auxiliary mercury well 14 communicating with the well 1 and provided with an adjustable plunger 15.

The mercury immersed electrode provides 60 an electrical resistor of a value variable with the degree of immersion thereof and the differential windings 4 and 5 provide for raising and lowering said electrode to vary its degree of immersion. The electrode is pro- 65 vided with a spring 16 which, with the buoyant force of the mercury, normally positions the plunger 6 in a position of equilibrium with respect to the windings 4 and 5 where- 70 by said plunger will be subjected to an up- 75 ward pull upon preponderation of winding 4 and to a downward pull upon preponderation of winding 5. The latching pawls, however, under the influence of springs 17 and 18 respectively, normally engage the ratchet extension of the plunger 6 to lock the latter against movement in either direction, the ratchet teeth 19 and 20 being reversed and so disposed as to render the pawl 7 ef- 80 fective to prevent downward movement and the pawl 8 effective to prevent upward move- 85 ment. Thus, the plunger may be released for either upward or downward movement while being locked against reverse move- 90 ment, by selective disengagement of the pawls 7 and 8 from the ratchet teeth and the electromagnets 10 and 11 are provided for this purpose. Further, as will hereinafter appear, the electromagnet 10 is connected in circuit for response upon preponderation of the winding 5 while the electromagnet 11 is connected in circuit for response upon preponderation of winding 4, whereby the plunger will be automatically freed to re- 95 spond upon preponderation of either wind- ing for corresponding adjustment of the electrode 3, but locked against return move- 100 ment pending a reversal in preponderation of said windings.

Accordingly the windings 4 and 5 provide 100 for control of the regulator for increasing and decreasing the resistance of the circuit including the electrodes 3, to varying de- 105 grees determinable by the duration of pre- ponderation of one winding by the other while the latching pawls provide for main- taining the resistance adjustment thus ac- complished, without dependency upon con- tinued differential action of the windings. In other words, the regulator described pro- 110

vides for "follow up" regulation and furthermore provides for movement of the electrode 3 at varying speeds for accomplishment of such regulation, according to the 5 degree of differential action of the windings 4 and 5. On the other hand, the piston 13, which is attached to the electrode 3 and perforated to permit slow passage of the mercury therethrough, provides for dashing the 10 movement of the electrode for a given maximum speed of the latter. This tends to prevent overtravel of the electrode and consequent hunting action of the regulator.

Further, since the electrode is always immersed in the mercury, its adjustment will 15 effect continuous resistance variations as distinguished from step by step variations, thereby providing for variation of the resistance in small increments and decrements. 20 Also, the auxiliary mercury well 14 provides by adjustment of its plunger, for variation of the resistance of the controlled circuit through variation of the level of the mercury in the well 1. Thus the regulator 25 may be readily and accurately adjusted for any given normal resistance value.

The measuring apparatus shown comprises a fluid conduit 21 having therein an electrical heating element 22 and resistance thermometers 23 and 24, an electrical instrument 25 to measure the energy input of the heating element, a mirror type galvanometer 26 connected in a Wheatstone bridge including said resistance thermometers, and selenium 30 cells 27 and 28 subjected to beams of light reflected from the galvanometer through a screened lens 29, said selenium cells serving to control the above described regulator for regulation of the energy input of the heating 35 element. Also, in the apparatus shown a magnetic amplifier 30 is provided as a regulating medium between the source of supply for the heating element and the above described regulator, although it is to be understood that the latter might be employed 40 to directly control the energy input of the heating element.

The heating element is supplied with energy from an A. C. supply source L, L' and 50 the magnetic amplifier which has two windings 31 and 32, has the former winding connected in series with said heating element. On the other hand, the remaining windings 55 of the apparatus are supplied with direct current derived from the A. C. source through a transformer 33 and electroionic devices 34 and 35. These electroionic devices supply such direct current to a circuit 36-37 and the winding 32 of the magnetic 60 amplifier is connected across said circuit through the above described regulator whereby the regulator serves to vary the resistance of the circuit of said winding. And as will be understood an increase or decrease 65 in the current of the winding 32 of the mag-

netic amplifier effects a corresponding but amplified variation in the current through the winding 31. Thus the heating element may be regulated by very small current variations in the D. C. control circuit and 70 hence by slight movements of the regulator, said control circuit being traceable from conductor 37 through winding 32 of the magnetic amplifier by conductor 38 to terminal 2 of the regulator, thence through the 75 regulator to the actuating plunger 6 and by conductor 39 to conductor 36.

The aforesaid Wheatstone bridge, in which the galvanometer is connected, comprises the resistance thermometers 23 and 24 and resistances 40 and 41 and said bridge is connected by conductor 42 to conductor 36 and by conductor 43 to conductor 37. The bridge is so adjusted as to be balanced when the fluid flows at a given rate and the heating 80 element is subjected to a given input. Hence as the rate of flow varies, the bridge will become unbalanced and deflect the galvanometer in one direction or the other according to the variation in flow of fluid. 85 The galvanometer is subjected to a beam of light from a linear source X and the screen 44 of the lens through which light is reflected is provided with an opaque band which divides the reflected light into two beams for 90 the two selenium cells. Also, the sections of the screen, on opposite sides of the band, are shaded in reverse directions whereby the most opaque portion of the upper section is aligned with the least opaque portion of the 95 lower section, with the result that as the galvanometer mirror shifts it decreases the intensity of light reflected on one selenium cell while it correspondingly increases the intensity of light reflected on the other cell. 100 And such variations in the light reflected on the cells result in variations in the relative resistance values of said cells, which resistance variations are utilized as herein- 105 after set forth.

The regulator windings 4 and 5 are connected in parallel across the D. C. circuit 36-37 and each of said windings has one of the selenium cells included in series therewith. Hence assuming equal pulls of the 110 windings 4 and 5 in normal position of the galvanometer, the selenium cells will subject said windings to control by the galvanometer and hence to control by the rate of flow of fluid. More specifically, a given variation in flow of fluid will cause a given deflection of the galvanometer which in turn will effect a given variation in the relative resistances of the two selenium cells with a consequent given differential action of the 115 regulator windings. And as will be apparent the winding 4 will preponderate when the galvanometer is deflected in one direction, while the winding 5 will preponderate 120 when the galvanometer is deflected in a re- 125 130

verse direction. Also, it will be apparent that as the degree of preponderation varies with the degree of deflection of the galvanometer, the regulator will operate at a speed 5 varying with the magnitude of the variation in flow of fluid. Thus if the variation in flow of fluid is slight, the regulator will operate slowly, whereas if the variation in flow of fluid is large the regulator will operate 10 at an accelerated speed, with the result of meeting the demands thereon without an excessive operating speed and consequent hunting tendency.

More specifically describing the circuit 15 connections of the regulator, one of the parallel circuits thereof may be traced from conductor 36 by conductors 45 and 46 through winding 5, by conductor 47 through winding 10, by conductor 48 through the 20 selenium cell 28, by conductor 49 to conductor 37. The other circuit may be traced from conductor 36 by conductors 45 and 50, through winding 11, by conductor 51 through winding 4, by conductor 52 through selenium cell 27 to conductor 49 and thence 25 to conductor 37. Thus the connections are such that the latch controlling winding 10 is connected in series with the winding 5 while the latch controlling winding 11 is 30 connected in series with the winding 4, with the result that as the current through the windings 4 and 5 is increased, the current through the latch controlling windings will be correspondingly increased for selective 35 tripping of the two latches according to the preponderation of the former windings.

What I claim as new and desire to secure by Letters Patent is:

1. In an electric regulator, in combination, a regulating member, electromagnetic windings exerting opposing pulls on said member and means for positively locking said member against movement pending a preponderating pull by one or the other of 45 said windings.

2. In an electric regulator, in combination, a regulating member, electromagnetic windings exerting opposing pulls on said member and controllable for preponderation of either by the other for movement of said member in reverse directions selectively, and means to releasably lock said member against return movement after response to either winding, pending preponderation of the other winding.

3. In an electric regulator, in combination, a regulating member, electromagnetic windings exerting opposing pulls on said member and controllable for preponderation of either by the other for moving said member in opposite directions selectively and means to lock said member when in given positions against movement in either direction and to release said member upon 65 preponderation of either winding but only

for movement of said member in one direction.

4. In an electric regulator, in combination, a regulating member, electromagnetic windings exerting opposing pulls on said member and controllable for preponderation of either by the other for moving said member in opposite directions selectively and means for locking said member in any one of a plurality of positions and for releasing said member for movement in either direction while restricting the same against movement in the opposite direction for "follow up" operation of said regulator.

5. In an electric regulator, in combination, a regulating member, electromagnetic windings exerting opposing pulls on said member and controllable for preponderation of either by the other for moving said member in opposite directions selectively and means for locking said member in any one of a plurality of positions and for releasing said member for movement in either direction while restricting the same against movement in the opposite direction, said 90 means having control windings in circuit with the former windings for the purpose set forth.

6. In an electric regulator, in combination, a regulating member, differential operating windings therefor, means to control said windings for preponderation of either by the other whereby said member may be moved in opposite directions and means to lock said member when in given positions 100 against movement in either direction, said last mentioned means being controllable by said first mentioned means to release said member for movement to any one of said positions in response to said windings while 105 restraining said member against return movement, pending a reversal of preponderance of said windings.

7. In an electric regulator, in combination, a regulating member, movable in opposite directions, means coacting with said member whereby the latter is normally locked against movement in either direction and lockable against movement in one direction selectively while being freed for movement in the opposite direction and electromagnetic means for control of the former means and operation of said member, including differential windings subject to control for preponderation of either by the 110 other.

8. In an electric regulator, in combination, a regulating member movable in opposite directions, means coacting with said member whereby the latter is normally 125 locked against movement in either direction and lockable against movement in either direction selectively while being freed for movement in the opposite direction, differential operating windings for said member,

electromagnetic means for controlling said locking means and means for effecting preponderation of either of said windings by the other and for controlling said electromagnetic means to effect release of said member according to the preponderance of said windings.

9. In an electric regulator, in combination, an adjustable device for effecting continuous resistance variations and electromagnetic control means for effecting adjustment of said device and for restraining the same after adjustment thereof, said means including differential windings for directly 15 adjusting said device.

10. In an electric regulator, in combination, an adjustable mercury immersed mem-

ber providing a variable resistance, differential windings for adjusting said member and means to releasably hold said member, 20 after adjustment thereof, for follow up regulation.

11. In an electric regulator, in combination, a mercury well, a member adjustable therein and having means associated therewith to limit the same to a given maximum rate of adjustment, electromagnetic means for effecting adjustment of said member and means to releasably hold said member, after 25 adjustment thereof, for follow up regulation.

In witness whereof I have hereunto subscribed my name.

ERWIN R. STOEKLE.
